UNITED STATES PATENT OFFICE.

JOSEPH E. STRAKER, JR., OF ATTLEBORO, MASSACHUSETTS.

DESIGN FOR A HANDLE OF SPOONS OR SIMILAR ARTICLES.

No. 39,472.

Specification for Design.

Patented Sept. 1, 1908.

Application filed June 13, 1908. Serial No. 438,407. Term of patent 7 years.

To all whom it may concern:

Be it known that I, JOSEPH E. STRAKER, Jr., a citizen of the United States, and residing in the town of Attleboro, in the county of Bristol and Commonwealth of Massachusetts, have invented a new, original, and ornamental Design for the Handle of a Spoon or Similar Article, which is illustrated in the accompanying drawing, forming part of this specification.

What I claim is:—

The ornamental design for the handle of a spoon or similar article as shown.

JOSEPH E. STRAKER, JR.

Witnesses:

C. E. GUILD,
H. A. MACKENNON.
